US00D841639S

(12) **United States Design Patent** (10) **Patent No.:** **US D841,639 S**
(45) **Date of Patent:** **** Feb. 26, 2019**

(54) **MOBILE PHONE CASE**

(71) Applicant: **SHENZHEN ZHIHAOTUO TECHNOLOGY CO. LTD**, Shenzhen, Guangdong (CN)

(72) Inventor: **Yuanping Liao**, Z Jin County (CN)

(73) Assignee: **SHENZHEN ZHIHAOTUO TECHNOLOGY CO. LTD**, Shenzhen, Guangdong Province (CN)

(**) Term: **15 Years**

(21) Appl. No.: **29/617,785**

(22) Filed: **Sep. 15, 2017**

(30) **Foreign Application Priority Data**

Aug. 16, 2017 (CN) 2017 3 0376590

(51) **LOC (11) Cl.** **14-03**

(52) **U.S. Cl.**

USPC **D14/250**

(58) **Field of Classification Search**

USPC D14/250

CPC H04B 1/385
